UNITED STATES PATENT OFFICE.

ERNEST H. BENNETT, OF EAST ORANGE, NEW JERSEY, ASSIGNOR TO JOHN H. BROMLEY AND EDWARD BROMLEY, COPARTNERS TRADING AS JOHN BROMLEY & SONS, OF PHILADELPHIA, PENNSYLVANIA.

DESIGN FOR A RUG.

SPECIFICATION forming part of Design No. 35,915, dated May 13, 1902.

Application filed April 22, 1902. Serial No. 104,230. Term of patent 3½ years.

To all whom it may concern:

Be it known that I, ERNEST H. BENNETT, a citizen of the United States, residing at East Orange, New Jersey, have invented and produced a certain new and original Design for a Rug, of which the following is a full, clear, and exact description, reference being had to the accompanying drawing, forming a part of this specification.

10 My invention relates to the surface ornamentation of a woven rug; and it consists of the novel design therefor delineated in said drawing.

The leading and distinguishing features 15 are a rectangular border ornamentation consisting of the connected irregular line figures *a*, arranged between parallel lines *b* *b*, the inner of which incloses the field center. In the center of the latter is a figure *c*, having 20 like opposite sides inclosing an arabesque

pattern *c'*. At each end of the field center are like figures *d* *d*, corresponding in general character to the opposite sides of the figure marked *c*, and in the space so formed are diamond-shaped figures *e*, the field spaces 25 and corners being filled in with other like arabesque patterns *c*² and line figures, respectively.

Having thus described my invention, what I claim as new, and desire to secure by Letters 30 Patent, is—

The design for a rug, substantially as shown and described.

In testimony whereof I have hereunto affixed my signature this 6th day of December, A. D. 1901.

ERNEST H. BENNETT.
